UNITED STATES PATENT OFFICE.

FREDERICK RASMUSSEN, OF HUNTERY, ILLINOIS, ASSIGNOR OF ONE-HALF TO FRANK B. HULLS, OF GARDEN PRAIRIE, ILLINOIS.

SLIDING-DOOR FASTENER.

No. 888,117.

Specification of Letters Patent.

Patented May 19, 1908.

Application filed July 17, 1907. Serial No. 384,267.

To all whom it may concern:

Be it known that I, FREDERICK RASMUSSEN, of Huntley, in the county of McHenry and State of Illinois, have invented certain new and useful Improvements in Sliding-Door Fasteners, of which the following is a specification.

The object of this invention is to construct a catch for car doors, in which the latch 10 thereof can be held against movement when the door is closed.

In the accompanying drawings. Figure 1 is a face view of the catch, in which the door is closed and is held locked against movement. Fig. 2 is a similar view in which the door is partly open. Fig. 3 is an edge view.

To the frame of the car adjacent to the door opening is secured a retainer bar 1 provided with an opening 2 in its underface, and 20 an opening 3 in its outer face.

To the door 4 is pivoted a latch 5 provided with the hooked end 6, and a slot 7 extending in the lengthwise direction of the latch. The end 8 of the slot 7 is curved downwardly. 25 A guide pin 9 is located in the slot 7 and serves as a support for the latch.

To the door 4 is secured a guide 10 overlapping the hook end of the latch.

Beneath the guide pin 9, and pivoted to 30 the door is located a weighted support 11 having its upper end beneath the latch. As shown at Fig. 1 the weighted support in conjunction with the guide pin 9 acts as a pivot for the latch. By moving the weighted support 11 so that the end 5 of the latch may drop, the latch can then be moved into the 35 position shown at Fig. 2, in order that the door may be closed without the latch engaging the retainer 1.

40 To the car frame is pivoted a weighted locking bar 12, and is located over the hook end of the latch, so that its normal position is over the latch. This locking bar will prevent the accidental raising of the latch.

45 An opening 13 is formed in the locking bar 12, and a seal 14 may be placed through this

opening and through the opening 3 in the retaining bar 1, thereby holding the latch against movement. Beneath the hook end of the latch is pivoted a weighted support 15. 50

In opening the door, the attendant removes the locking bar and rocks the weighted support 15 beneath the hook end of the latch as shown in dotted lines Fig. 1. The door can then be opened without the attendant holding the hook end of the latch up, and after the door has been opened, the weighted locking bar 12 and weighted support 15 will assume their normal positions shown in Fig. 2. In closing the door, the hook end of the 60 latch will move the locking bar 12 to permit the hook to engage the retainer bar 1.

I claim as my invention.

1. A sliding door fastener comprising a latch having a pivotal and longitudinal movement in connection with a door, a retainer for the latch located intermediate its ends, and a weighted pivotal support for the pivoted end of the latch and located beneath the latch. 70

2. A sliding door fastener, comprising a latch having a pivotal connection with the door, a retainer for the latch, and a free moving weighted pivotal support for the hook end of the latch and located below the hook 75 end of the latch.

3. A sliding door fastener comprising a latch having a slot extending in its lengthwise direction and having a downturned portion, a stud located in the slot, a retainer for the latch located intermediate its ends, and a weighted pivotal support located beneath the latch and adjacent to the downturned portion of the slot. 80

In testimony whereof I have hereunto set 85 my hand in presence of two subscribing witnesses.

FREDERICK RASMUSSEN.
